UNITED STATES PATENT OFFICE.

ZACHARIAH N. T. MILIRONS, OF CUTHBERT, GEORGIA.

DESIGN FOR A COTTON-SCRAPER.

SPECIFICATION forming part of Design No. 30,241, dated February 21, 1899.

Application filed January 26, 1899. Serial No. 703,512. Term of patent 14 years.

To all whom it may concern:

Be it known that I, ZACHARIAH N. T. MILIRONS, a citizen of the United States, residing at Cuthbert, in the county of Randolph and 5 State of Georgia, have invented and produced a new and original Design for a Cotton-Scraper, of which the following is a specification.

This invention relates to a new and original 10 design for a cotton-scraper; and it has for its object to provide a design of this character that shall be both useful and ornamental.

The leading feature of the design resides in 15 a crescent-shaped blade provided centrally between its ends, in the front edge thereof, with a reentrant curved notch.

While the essential feature of the design resides in the crescent-shaped blade provided with the curved notch in the front edge thereof 20 of a central point, the invention also embodies several minor features. These minor features are the crescent-shaped blade having the concaved edge at the rear thereof and a convexed edge at the front, while also being 25 of a tapering thickness in cross-section and forming a beveled cutting front edge.

Additional minor features of the design are 30 the front and rear edges of the blade meeting in V-shaped points at the terminals thereof and the blade being sigmoidally curved in a longitudinal direction and provided with a circular hole centrally between its ends.

In the drawings, Figure 1 is a perspective 35 view of a cotton-scraper embodying the herein-described design. Fig. 2 is a plan view

thereof. Fig. 3 is a cross-sectional view on the line 3 3 of Fig. 2. Fig. 4 is a rear edge view of the blade.

Referring to the accompanying drawings, the numeral 1 designates the cotton-scraper 40 blade, which is of a crescent shape and provided with a concaved rear edge 2 and the convexed front edge 3, said convexed front edge being beveled upon both sides and the blade being of a tapering thickness in cross-section 45 from the rear to said front edge.

The crescent-shaped blade has the front and rear edges thereof meet in V-shaped points 4 at the terminals of the blade, and centrally between these points the said blade is provided in its front cutting edge 3 with a central reentrant curved notch 5, directly in rear of which notch and between the front and rear edges of the blade the latter is further provided with a circular hole 6. 55

In addition to the features described the scraper-blade is bowed or dished and has a sigmoidal curvature in a longitudinal direction.

What is claimed is— 60

The design for a cotton-scraper, herein shown and described.

In testimony that I claim the foregoing as my own I have hereto affixed my signature in the presence of two witnesses.

ZACHARIAH N. T. MILIRONS.
